CLAIM

The ornamental design for a display unit, as shown and
described.

DESCRIPTION

FIG. 1 is a photograph of a front perspective view of a display unit showing my new design;
FIG. 2 is a front elevational view thereof, the rear view being
a mirror image of FIG. 2; and,
FIG. 3 is a side elevational view thereof, the other side being
a mirror image of FIG. 3.

1 Claim, 3 Drawing Sheets

FIG. 1

FIG. 2

FIG. 3
